WATER GAS PRODUCTION

William Vaughn Duke, Germantown, Pa., as-
signor to Carsten I. Johnsen, Floral Park, N. Y.

Application November 9, 1928, Serial No. 318,241

3 Claims. (Cl. 48—206)

This invention relates to water gas generation, that is, to a method of manufacturing water gas, either carbureted or not, and to a water gas generator having, if desired, a carburetor associated with it. It involves also a superheating of the product. The objects of the invention are (1) to provide a method of continuous water gas manufacture and a water gas generator that is capable of continuous operation; (2) to effect an economy in the consumption of fuel, in the installation cost of the generator and in the cost of operation; (3) to simplify the construction of the generator; (4) to reduce the size of the generator without loss of productive capacity; (5) to provide an automatic generator; (6) to eliminate certain operating conditions which are destructive of the materials of which the generator is built; (7) to provide a water gas generator in which pulverized coal may be used effectively as a fuel; (8) to improve a water gas generator in point of simplicity of construction and of efficiency of operation, and (9) to provide a method of carbureting water gas and of superheating it and to provide a generator construction in which this method may be carried out.

The method and two modifications of an apparatus embodying the invention are described hereinafter and are illustrated in the accompanying drawings.

30 In the drawings—

Figure 1 is a vertical sectional view through a water gas generator constructed in accordance with this invention.

Figure 2 is a fragmental view, in section, on the line 2—2 of Figure 3, showing the manner in which the heating tubes are arranged.

Figure 3 is a fragmental view, namely in longitudinal section through the group of tubes shown in Figure 2.

40 Figure 4 is a view, in section in a vertical plane, of a modified combustion chamber.

Figure 5 is a fragmental view, in vertical section on the line 5—5 of Figure 4, showing the arrangement of secondary air inlet passages in the modified combustion chamber shown in Figure 4.

50 The generator shown here has a combustion chamber 10, a water gas generating chamber 11, a carbureting chamber 12 and a superheating chamber 13, all formed within a single structure.

This structure is built of fire brick or other refractory material and, in its structural details, 55 may conform to any usual or desirable practice in

furnace design. The details of construction are not a part of this invention.

A number of tubes 14, triangular in cross-section, extend from the partition 15 between the combustion chamber and the water gas generating chamber through the partitions 16 and 17, which separate the carbureting chamber 12 respectively from the generating chamber 11 and the superheating chamber 13, and thence to the end wall 18 of the superheating chamber. The back wall 19 of the whole structure and the end wall 18 of the superheating chamber form together a header to which the tubes deliver and from which a duct 20 leads to a stack or to any other device for utilizing or for disposing of the remaining heat of the combustion gases. A door 21 is provided at the bottom of this header for the removal of any ash or other solid matter deposited within the header.

Each of the tubes 14 has flanged ends 22, those at each end abutting one another so that one end of the group or stack may be received in an opening in the partition wall 15 and the other end in a similar opening in the partition 18. The joints between the several tubes and between the group of tubes and the partitions may be sealed, if desired, but that is not necessary since the pressures in adjoining chambers may be maintained sufficiently near to equality to prevent undesirable flow of gas from one chamber to another. The flanges conform in shape to the tubes but, being of larger size, they abut each other on all sides and therefore present to the combustion chamber what is, in effect, an apertured wall. Similarly, there need be no sealed joints between the tubes and the intermediate partitions 16 and 17. The snug fit obtained by building the refractory material of these walls with apertures just large enough to receive the tubes is sufficient.

95 The tubes are stacked so as to occupy the relative positions shown in Figure 2, thus forming horizontal passages and a number of diagonal intersecting passages between them. A satisfactory material of which to make the tubes is carborundum. The use of other refractory materials is possible.

On the top of the combustion chamber is a fuel feeder of a well known marketed type designed to deliver a combustible mixture of air and pulverized coal or similar fuel under pressure to the combustion chamber. The coal is introduced to the feeder from the duct 23 and primary air under pressure is led in by the duct 24, this primary air being used to force the pul- 110

verized coal into the combustion chamber. Additional air for the mixture is drawn in through the port 25 by the stream of primary air and coal. At the bottom of the combustion chamber 5 is a door 26 giving access to the chamber for removal of the heavier products of combustion which fall to the floor of the chamber.

When ignited, the combustible mixture delivered under pressure burns within the combustion chamber and produces a body of highly heated gases of combustion which enters the tubes 14 and passes through them to the header between the end walls 18 and 19 and thence to the duct 20. In passing, these gases lose heat 15 to the walls of the tubes and thus there is provided in the producer, carbureting and superheating chambers a number of spaced bodies, heated to a high degree and capable of heating any bodies which come in contact with them.

20 Above the gas generating chamber is a device for delivering steam and pulverized coal, intimately mixed and under pressure, past the tubes, i. e., the region through which the tubes pass and into contact with the tubes. This device 25 consists of a screw conveyor 27 for delivering pulverized coal from a hopper 28 to a down duct 29 and a nozzle 30 which is connected to a source of steam and which delivers to the center of the down duct 29 at about the point where the pulverized coal is fed in.

30 Just below this point is a nozzle 34 through which water gas under pressure is delivered. The water gas forms the motive jet, aided, it may be, by the steam jet, and forces the mixture of coal 35 and steam against and between the tubes in the top layer. The construction of such a pressure feeder is known but, as will be described more fully hereinafter, the use of water gas to deliver the coal or other carbonaceous product is an important part of this invention.

35 The pressure of the delivery causes the mixture of coal and steam to pass in a baffled course between the tubes in direct contact with the heated walls hereof or in such close proximity thereto that the particles of coal and steam receive the heat of the tubes. The usual chemical reaction of carbon and water, when heated to the proper temperature, takes place and the water gas generated thereby is forced to the bottom of 50 the generating chamber.

An opening 31 in the partition 16 permits the water gas to pass into the lower region of the carbureting chamber 12 from which it is forced, by the pressure behind it, upward in a baffled course 55 between the tubes to the top of the carbureting chamber. An opening 32 in the partition 17 leads the carbureted gas, the product of the carbureting chamber, to the superheating chamber 13 where they flow downward between the tubes 14 60 and pass through the outlet port 33 to a storage means or to other apparatus for further treatment.

The carburetion is effected by a spray of liquid hydrocarbon delivered in a downward direction 65 at the upper part of the carbureting chamber by a nozzle 54. The force of the spray is sufficient to cause the oil to pass downward between the tubes counter current to the water gas flowing from the gas generating chamber. The gas and 70 the oil are thus intermixed thoroughly by their interfering baffled flows and, since this mixing occurs in contact with the heated tubes and in the region heated by the tubes, the water gas is well carbureted.

75 The carbureted gas in passing through the

chamber 13 is heated to a higher temperature which improves the carburetion and generally fixes the conditions created in the gas generating and carbureting chambers.

80 A valved inlet duct 35 is provided to introduce air into the gas generating chamber to burn out the carbon deposit which in time accumulates on the tubes. In starting up the gas generating, it may be desirable to burn in the generator chamber 11 the pulverized coal from the hopper 28 before the steam supply is begun in order to bring the tubes to the proper temperature in a shorter time. For this purpose, the duct 35 supplies air to support combustion within the gas generating chamber. During the normal water gas generating operation the duct 35 is closed.

85 The combustion chamber may be built in two parts, in one of which only the primary air is consumed to give principally carbon monoxide while in the second part additional air is supplied to give the dioxide of carbon. Such a chamber is shown in Figure 4. The fuel is delivered under pressure to the first part 40 of the chamber, between the front wall and the mid partition 41, by the primary air supplied by the duct 24' leading to the feeder 42. The partition 41 dividing the chamber into two parts is hollow, being made up of two spaced walls 43, 44. The secondary air is supplied by the duct 45 to the interior space between the walls 43, 44 and is delivered to the 100 second part 46 of the combustion chamber by the entraining action of the carbon monoxide gas flowing from the first part to the second part.

90 For this purpose a number of short tubes 47 extend through both walls 43, 44 of the partition 110 41, being supported by the wall 43 on the side toward the first part of the combustion chamber. Each tube 47 is spaced from the surrounding portion of the other wall 44 leaving an annular flow passage 50 connecting the interior of the partition and the second part of the combustion chamber. The corners of the space 50 between each tube and the surrounding part of the wall 44 are blocked by fillers 48 to constrict the flow passage over a portion of its length thus increasing the 115 entraining action at the mouth of the tube. An additional passage 49 connects the two parts of the combustion chamber and permits the removal of solid matter from the second part as well as from the first. The hot gas produced by the 120 combustion passes through the flues 14 just as in the modification shown in Figure 1.

125 Considering the manner of generating the water gas, and of carbureting and superheating it, apart from any particular structure by which the 130 gas is made and treated, it will be evident that a new method is involved. The essential elements of the method are that a flow of heated gas is effected on one side of, or, more specifically, inside of, each of a number of heat conducting 135 bodies while a flow of a carbonaceous product and water is effected on the other side of each of the same bodies so that the heat of the gas is transferred to the carbon and the water and the water gas reaction is brought about. The word water 140 is used herein in a generic sense to cover the liquid or vapor form of the substance which provides the hydrogen and oxygen for the water gas reaction. While the vapor form or steam is preferred, it is possible to use the liquid form.

145 In the customary practice a refractory material is first heated and then, after the application of heat is discontinued, the carbonaceous product and the water are brought in contact with the refractory material until all of the heat is given up.

In contradistinction to this practice, the present process may be carried on continuously since heat is added to the refractory body as fast as it is absorbed in the water gas reaction. The carburetion is effected by leading the water gas back over another portion of the body being heated by the flow of hot gas. So also with the superheating.

In addition to the greater economy and convenience inherent in a continuous process, there are afforded by this invention, and particularly by the preferred form disclosed here, marked advantages in the low cost of installation, operation and maintenance. The design is simple and requires for the most part only standard equipment readily obtained in the market and structure easily built. Powdered coal is used both as fuel in the combustion chamber and as the carbonaceous product for the water gas reaction effected in the generating chamber. Such coal is consumed efficiently for both purposes in the present construction so that a maximum of available energy is utilized. Once the process is begun, there need be no interruption for a considerable time. The delivery of the various feeders and the supply of air may be predetermined and the apparatus set accordingly, after which little attention is necessary. When, in time, a deposit does form on the tubes it is not necessary to scrape them or to employ mechanical methods of removal which endanger the material of the tubes, but instead, coal is burned in the generating chamber to remove the deposit.

A particularly useful feature is the utilization of water gas to introduce the coal into the generating chamber. It is important to introduce the coal and the steam as a spray and under sufficient pressure to carry them past the tubes to the bottom of the chamber. If it is attempted to use the steam or to use air to introduce the coal, a difficulty is encountered in obtaining the proper proportions of the ingredients for the water gas reaction. By using water gas, that difficulty is avoided. I therefore regard this as an important part of the invention.

Other merits and utilities of the invention will be apparent to those using it or interested in the art in which it may be used and it is deemed unnecessary to mention all of them here. Variations from the disclosed embodiment, either as a result of ordinary skill or of further invention, are possible within the fair scope of this invention. Therefore, with the intention of protecting all of the features of the apparatus and process, the invention is defined in its substantial scope in the following claims.

I claim:

1. The method of manufacturing water gas which comprises the continuous internal heating of a number of spaced hollow bodies and utilizing the entraining action of a current of water gas to carry pulverized coal and steam in proper proportions to form water gas between said bodies and in contact therewith.

2. The method of manufacturing water gas which comprises the continuous internal heating of a number of spaced hollow bodies, entraining pulverized coal and steam in portions to form water gas between portions of said bodies and in contact therewith by a carrying current of water gas passing the newly formed gas and carrying gas current past other portions of said hollow bodies and spraying a liquid hydrocarbon upon said other portions of said hollow bodies in a direction opposite to the gas current flowing past said bodies.

3. The method of manufacturing water gas which comprises the continuous internal heating of a number of spaced hollow bodies, entraining pulverized coal and steam in portions to form water gas between portions of said bodies and in contact therewith by a carrying current of water gas passing the newly formed gas and carrying gas current past other portions of said hollow bodies and carburetting said gas with an enriching hydrocarbon gas in the region of said other portions of said hollow bodies.
